UNITED STATES PATENT OFFICE.

MARCUS BLOOM, OF CHARLOTTE, NORTH CAROLINA, ASSIGNOR TO ICY-O METAL PRODUCTS COMPANY, INCORPORATED, OF CHARLOTTE, NORTH CAROLINA.

DISPENSING CABINET.

Application filed November 26, 1928. Serial No. 677,094.

This invention relates to cabinets and has for an object the provision of a cabinet or container designed for the attractive display and sale of bottled goods.

5 Another object of the invention is the provision of a self-serve dispensing cabinet for bottled or other goods which are kept for sale in a cool palatable condition, means being provided whereby the particular kind of 10 goods desired may be quickly and conveniently reached without opening the cabinet for a sufficient period to appreciably lower the temperature upon the interior thereof.

Another object of the invention is the provision of a cabinet of this character having a dispensing chamber provided with a removable top, so that the said chamber may be conveniently filled by the removal of said top, while a relatively small dispensing door 20 is provided for the sale of the contents of the chamber, combined means being provided for locking the removable top and the dispensing door in closed position.

With the above and other objects in view, 25 the invention further includes the following novel features and details of construction, to be hereinafter more fully described, illustrated in the accompanying drawings and pointed out in the appended claims.

30 In the drawings:—

Figure 1 is an elevation of a dispensing cabinet constructed in accordance with the invention.

Figure 2 is a top plan view of the same.

35 Figure 3 is a vertical central section.

Figure 4 is a section on the line 4—4 of Figure 3.

Figure 5 is a fragmentary section taken substantially on the line 5—5 of Figure 1.

40 Figure 6 is a detail elevation of the display rack and card holder.

Figure 7 is a section on the line 7—7 of Figure 6.

Fig. 8 is a vertical sectional view.

45 Referring to the drawings in detail wherein like characters of reference denote corresponding parts, the cabinet as shown comprises a casing 10 which includes an upper chamber 11 and a lower chamber 12, 50 while extending from the latter are supporting legs 13. The casing may be of any suitable size and configuration, the one shown being substantially cylindrical with the lower chamber 12 tapering from its top toward 55 the bottom thereof.

The upper chamber 11 which will be hereinafter referred to as a dispensing chamber is provided with insulated side walls 14 and a bottom wall 15, the top of the said chamber being formed by a removable insulated 60 cover 16.

The cover 16 is provided with an annular flange 17 and is removably held in place by means of pins 18 which extend from the casing and which engage bayonet slots 19 provided in the flange 17. By partly rotating the cover, the latter may be readily removed so that goods to be sold may be placed within the dispensing chamber.

Located within the dispensing chamber 11 is a container 20 which is shaped to conform to the shape of said chamber and is slightly spaced from the bottom and side walls of the latter. This container is designed to contain the goods to be sold and ice within which the goods may be packed to keep them in a cool palatable condition. The container 20 is rotatable within the chamber 11 and for this purpose there is provided a rod 21 which extends downwardly through the 80 cover 16 and through the container 20 and has its lower end mounted in a bearing 22. Secured to the rod 21 are radially disposed arms 23 whose outer ends are secured to the walls of the container 20 so that the said 85 rod will hold the container in proper position for and provide means whereby the container may be rotated. The purpose of this is to bring the particular kind of goods desired by the purchaser into position beneath 90 a dispensing door 24, the latter being hingedly connected to the cover 16 as shown at 25. The rod 21 is provided with a removable crank arm 26 whereby the container may be rotated.

Hingedly secured to the casing 10 as shown at 27 is a hasp 28 which is designed to engage over a staple 29 carried by the door 24 so that the latter may be locked in closed position. In addition, the flange 17 of the cover 16 has extending therefrom a pin 30 which is adapted to pass through an opening 31 provided in the hasp 28 so that when the door 24 is locked, the cover 16 will also be locked and rotation and removal of 105 the latter prevented.

The bottom of the container 20 is provided with drain openings 32 through which water from the container may run into the dispensing chamber 11, a drain pipe 33 lead- 110

ing from the bottom of this chamber into the chamber 12. A drain opening 34 in the bottom of this last mentioned chamber is located above a pan 35, so that water collected from melted ice within the container 20 will run into this pan.

The chamber 12 is designed to provide a storage chamber for empty bottles and the like and this chamber is provided with a door 36 which is hinged to the casing as shown at 37 and is provided with a hasp and staple 38 so that it may be locked in closed position. The casing is provided with a decapper 39 for the removal of seals from the bottles, the said seals being adapted to fall into a hopper 40 and to pass from the said hopper through an opening 41 in the casing into a container 42 removably located within the storage chamber 12.

20 The cover 18 is provided with knobs or handles 43 for convenience of removal. In addition, the cover may be provided with a display rack or stand 44 so that the goods for sale may be placed thereon as shown in 25 Figure 1 of the drawings. In addition, this rack is provided with a removable card holder 45 which is illustrated in detail in Figures 6 and 7 of the drawings and which is provided with a grooved flange 46 for engagement over the edge of the display rack 44.

As shown in Figure 8, the lower chamber 12^a may if desired also be provided with insulated walls 47 so that the said chamber 35 may provide a storage chamber for keeping the supply of goods in a cold condition before placing them within the container 20. In this form of the invention, the dispensing chamber 11 is provided with a drain opening 48 whereby water collected within the chamber may be conveniently drawn off, while the chamber 12^a is provided with a drain opening 49 which is positioned above the pan 35 as previously described.

45 The invention is susceptible of various changes in its form, proportions and minor details of construction and the right is herein reserved to make such changes as properly fall within the scope of the appended 50 claims.

Having described the invention what is claimed is:—

1. A cabinet comprising a casing divided into upper and lower compartments, a removable cover for said casing having a central opening, a container arranged within the upper compartment and spaced from the bottom and walls thereof, a rod arranged centrally of the container and journaled in the bottom of the upper compartment and projecting through the opening in the cover, a handle on the upper end of the rod for rotating the latter, spaced sleeves secured to said rod within the container, radially disposed arms projecting from diametrically

opposite sides of each sleeve and having their outer extremities offset and secured to the wall of the container, whereby the latter is mounted for rotation with the rod, a drain pipe depending from the bottom of the upper compartment and establishing communication between the respective compartments, and the bottom of said container having a plurality of drain openings through which the water is allowed to escape from the container to said pipe.

2. A dispenser of the kind indicated comprising a casing, a cover closing the casing at one side and removable to fully expose the interior of the casing, a door closing a hand hole in said cover, and means carried by the casing and engageable with the door to simultaneously lock the latter and the cover in closed positions.

3. A dispenser of the kind indicated comprising a dispensing chamber, a cover closing the chamber at one side, a container rotatably mounted in the chamber and having an unobstructed open side disposed in facing relation to said cover, the cover-closed side of the dispensing chamber being unobstructed to the open side of the container when the cover is in open position, whereby free access is had to the container for charging with goods and a refrigerant, and an actuating crank operatively connected with the container and disposed centrally of the cover when the latter is in closed position, the cover having a door closing an opening of relatively small area through which the selective removal of the goods from the container may be made as the container is actuated by said crank.

4. A dispenser of the kind indicated comprising a dispensing chamber, a cover closing the chamber at one side, a container rotatably mounted in the chamber and having an unobstructed open side disposed in facing relation to said cover, the cover-closed side of the dispensing chamber being unobstructed to the open side of the container when the cover is in open position, whereby free access is had to the container for charging with goods and a refrigerant, a shaft supporting the container and extending through and journaled in the cover, the shaft having a bearing at the closed side of the container, and a detachable crank engaged with the projecting side of said shaft, the cover having a door closing an opening of relatively small area through which the container is accessible throughout as the shaft is rotated.

5. A dispenser of the kind indicated comprising a dispensing chamber, a cover closing the chamber at one side, a container rotatably mounted in the chamber and having an unobstructed open side disposed in facing relation to said cover, the cover-closed side of the dispensing chamber being un-

obstructed to the open side of the container when the cover is in open position, whereby free access is had to the container for charging with goods and a refrigerant, the container having a shaft rotatably supporting it in the dispensing chamber, said shaft having a thrust bearing in the bottom of the dispensing chamber and a bearing in said

cover, and a crank handle detachably engaged with the shaft exterior of the cover, 10 the latter having a door closing an opening of relatively small area to permit access to all parts of the container as the shaft is rotated.

In testimony whereof I affix my signature.
MARCUS BLOOM.
